United States Patent Office.

JOHN M. WHEELER AND CHARLES W. CHASE, OF BATAVIA, IOWA.

Letters Patent No. 96,065, dated October 19, 1869.

IMPROVED CAR-COUPING.

The Schedule referred to in these Letters Patent and making part of the same.

To all whom it may concern:

Be it known that we, JOHN M. WHEELER and CHARLES W. CHASE, of Batavia, in the county of Jefferson, and State of Iowa, have invented a new and useful Improvement in Car-Couplings or Buffers; and we do hereby declare that the following is a full, clear, and exact description of the same, reference being had to the annexed drawings, making part of this specification, in which—

Figure 1 is a longitudinal vertical section, through the centre of A of fig. 2.

Figure 2 is an elevation of two buffers, shown as coupled together, the coupling-hook and link being shown in dotted lines.

Corresponding letters represent corresponding parts in both figures.

This invention relates to that class of car-connections known as "self-couplers;" and

It consists in the combination and arrangement of its parts, as will be more fully explained herein-after.

A represents a buffer, which may be of cast or wrought-metal, and it is to have a recess or chamber formed in its centre, for the reception of the coupling-hook C. It also has an opening through its front end, for the insertion of the coupling-link.

A', in fig. 2, represents a buffer as coupled to A in the same figure, and shows how the same may be used to couple two cars together, one of which is supplied with our improved coupling, while the other has only the ordinary or usual buffer.

B represents a prolongation upon the rear end of the buffer, to which may be secured bars of wrought-iron, for securing the buffer to the frame-work of the car.

C represents the coupling-hook, which is to be placed within the recess or chamber formed in the buffer, and is to be pivoted to the side walls thereof, as shown at a, figs. 1 and 2, where it is seen as having its forward end, or a hook formed thereon, passing through the aperture formed in the coupling-bar or link, and resting in a recess formed in the lower portion of the buffer, while its rear end rests upon a spring, as shown in fig. 1, the object of which is to prevent the hook from rising out of the link in consequence of the jars or concussions to which the cars are subjected while in motion.

The arrangement of this hook within the buffer is such, that as the force is applied to move the car, the hook will be drawn forward, in consequence of the yielding of the spring G, until its front end comes in contact with the projection on the end of the buffer, when the entire force will be exerted upon the spring, which may be attached to the inner end of such buffer.

D represents the coupling-bar or link, which is to be constructed with an aperture in its front end, for the reception of the hook of the buffer, or the hooks of both buffers, when both are supplied with such hooks.

At a short distance from the aperture or opening above described, there is to be formed another aperture, which may be a hole bored through the link or bar, or it may be slightly elongated, it being for the reception of the coupling-pin, when such device is used.

That end of this link or bar which is opposite to the one just described, is to be solid, or without apertures or openings, for the purpose of making it heavy, or constituting it a weight, so that when it is drawn out of the buffer, it shall at once fall down to and rest upon the lower portion of the buffer, which will form a fulcrum for the link to rest upon, which will cause its inner end, or the one which remains in the buffer, to be raised, and thus all danger of the bar being jarred or shaken out of the buffer will be avoided.

E represents a rope or chain, which is to be attached to the upper side of the coupling-hook, and is to pass up through a slot or aperture formed in the upper wall of the buffer, and may extend to the top of the car, if desired, it being for the purpose of raising the hook out of the link when it becomes necessary to uncouple the cars, or to remove the link or bar from the buffer.

F represents a rubber or other spring, which is to be placed under the rear end of the hook, and held in its position by means of a plate of metal, which is to be secured to the under side of the buffer, the object being to have the spring always in contact with the coupling-hook, and in the rear of the fulcrum or of such hook, so as to keep its forward end from rising, and allowing the coupling-link to pass out of the buffer when the cars are in motion.

G represents a spring, which may be of rubber or of steel, it being placed in a slot formed in the side of the buffer, and in front of the pin or bolt a, which forms the fulcrum of the coupling-hook C. The arrangement of this spring is such, that when power is applied to move the car, the same will be transmitted through this spring, and thus the parts will be relieved from the sudden jar usual in such cases.

We have described only one spring, and its application to one side of the buffer, but it is our intention to use two, one upon each side thereof.

Having thus-described our invention,

What we claim, and desire to secure by Letters Patent, is—

1. The combination and arrangement of the coup-

ling-hook C and spring F, and the buffer A, substantially as and for the purpose specified.

2. The arrangement of the coupling-hook C and spring G, with reference to the projection upon the interior of the buffer, as a consequence of which the longitudinal movement of the coupling-hook is arrested, substantially as and for the purpose set forth.

In testimony whereof, we have signed our names to this specification, in the presence of two subscribing witnesses.

JNO. M. WHEELER.
CHARLES W. CHASE.
